US0D1092741S

(12) **United States Design Patent** (10) Patent No.: **US D1,092,741 S**
(45) Date of Patent: ** Sep. 9, 2025

(54) **X-RAY APPARATUS**

(71) Applicants: **THALES**, Meudon (FR); **BA
HEALTHCARE**, Pacé (FR)
(72) Inventors: **Guillaume Royer**, Vélizy-Villacoublay (FR); **Jean-Baptiste Guirimand**, Moirans (FR); **Stefania Nuzzo**, Vélizy-Villacoublay (FR); **Nicolas Coustaub**, Vélizy-Villacoublay (FR); **David Pottier-Vincent**, Pacé (FR); **François Rieffel**, Pacé (FR)
(73) Assignees: **THALES**, Maudon (FR); **BA
HEALTHCARE**, Pace (FR)

(**) Term: **15 Years**

(21) Appl. No.: **35/520,770**

(22) Filed: **Apr. 18, 2024**

(80) **Hague Agreement Data**

Int. Filing Date: **Apr. 18, 2024**
Int. Reg. No.: **DM/236680**
Int. Reg. Date: **Apr. 18, 2024**
Int. Reg. Pub. Date: **May 3, 2024**

(30) **Foreign Application Priority Data**

Nov. 25, 2023 (EM) 015042308-0001
Nov. 25, 2023 (EM) 015042308-0002

CLAIM

The ornamental design for x-ray apparatus as shown and described.

DESCRIPTION

1. X-ray apparatus
2. X-ray apparatus
- 1.1 : Perspective
- 1.2 : Front
- 1.3 : Back
- 1.4 : Left
- 1.5 : Right
- 1.6 : Top
- 1.7 : Bottom
- 2.1 : Right
- 2.2 : Left
- 2.3 : Front
- 2.4 : Top
- 2.5 : Bottom
- 2.6 : Back
- 2.7 : Exploded

1 Claim, 14 Drawing Sheets
